(57) **CLAIM**

The ornamental design for an electrical contact as shown and described.

DESCRIPTION

FIG. 1 is a top, front, left perspective view of the claimed design for an electrical contact;

FIG. 2 is a bottom, front, right perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The broken lines immediately adjacent to the shaded area depict boundaries of the claimed design and form no part thereof. The broken lines showing the remainder of the electrical contact depict environmental structure and form no part of the claimed design.

1 Claim, 8 Drawing Sheets
